CLAIM

The ornamental design for a combined hunting belt and bandolier, substantially as shown and described.

DESCRIPTION

FIG. 1 is a front perspective view of an unfastened combined hunting belt and bandolier showing my new design;

FIG. 2 is a front perspective view thereof showing the combined hunting belt and bandolier fastened.

FIG. 3 is a frontal elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.
